HIGHWAY GATE

William J. Buford, Houston, Tex.

Application May 15, 1937, Serial No. 142,757

6 Claims. (Cl. 39—1)

The invention relates to a highway gate which is particularly adapted for arrangement such that it will protect railroad crossings or other intersections where it is desired to stop the traffic at an intersection.

It is one of the objects of the invention to provide a gate which will be automatically raised and lowered in accordance with a signal imparted thereto and to permit movement of the gate in event of an impact therewith.

Another object of the invention is to provide a support arrangement for gates which includes a framework so that the gate will be enclosed in raised position.

Still another object of the invention is to provide a yieldable cable arrangement so that in event there is an impact against the gate the gate will be allowed to move a predetermined distance so as to assist in resisting the impact.

Still another object of the invention is to provide a gate wherein weights must be lifted when the gate is moved laterally from its normal position so that the raising of these weights will tend to oppose the lateral movement of the gate and bring the object causing the impact to rest.

Other and further objects of the invention will be readily apparent when the following description is considered in connection with the accompanying drawings wherein:

Fig. 1 is a transverse vertical section showing the general arrangement of the operating mechanism, the gate and its supports, in position across the highway.

Fig. 2 is a section taken on the line 2—2 of Fig. 1 and looking downwardly upon the operating mechanism.

Fig. 3 is a top plan view of the support frame.

Figs. 4 and 5 are sectional views taken on the line 4—4 and 5—5, respectively, of Fig. 1.

Fig. 6 is a vertical sectional view of a modified arrangement of the apparatus where the counter-weights are disposed in separate housings above the surface.

In Fig. 1 the highway is indicated generally at 2 and disposed adjacent each side thereof are the support posts 4 and 5. These posts are of sufficient height so that they may suitably support the gate 6 in raised position so as to permit the passage of traffic beneath the gate. A framework 7 is arranged across the top of the posts 4 and 5 in order to suitably space them apart and to carry the display area 8 upon which advertising material may be positioned. This frame 7 also serves to enclose the gate 6 and protect it from the elements. Suitable brace

wires 10 are arranged on each side of the framework 7 and rod 11 connects the opposite posts at the top.

In order that the gate 6 may be movable vertically to its open position as seen in Fig. 1, or dropped down to its closed position across the highway, the gate is mounted for movement with the cables 14 and 15, one of which is carried by each of the supports 4 and 5. The gate is attached to these cables at its top by the clamp member 17, which is best seen in section in Fig. 4, the rod 20 being the end rod of the gate 6 and the cable 14 is shown as clamped in position by this member 17.

In Fig. 5 the end rod 20 of the gate is clamped 15 securely in position by the clamp 22, but this clamp is somewhat different from the clamp 17 in that it carries a roller 23 mounted on the pin 24 so as to engage the cable 14. In this manner the gate may move relative to the bottom portion of the cable but is secured thereto by the upper clamp 17. Both ends of the gate are connected in this manner. If desired, the rod 20 may be a cable construction so that there will be no rigid portions in the gate, it being understood that the strands 25 of the gate proper may be flexible cables so that as little damage as possible will be caused by an impact against them.

In order to move the cables 14 and 15 a motor 30 has been provided in the housing 31. This motor carries a worm 32 to engage the gear 33. Rotation of this gear imparts rotation to the shaft 35 upon which is mounted the drum 36. This drum is divided into two parts, 37 and 38, in order to receive the cables 14 and 15, the drum 37 receiving the cable 15 and the drum 38 receiving the cable 14. The cable 14 passes over the sheave 40, which is mounted on the pin 41 in the top of the support 5 and thence passes downwardly beneath the guide roller 42 past and over the guide roller 43. The cable then passes downwardly around one of the support rollers 46 thence upwardly around a roller 45 and then around the drum 38. Several turns of the cable are passed around the drum 38 and 45 the cable then leads away from the drum to the other guide roller 45. It then passes downwardly and beneath one of the support rollers 46 and then over the guide 47 upwardly to the guide 48 which is carried by the support post 5 and then over the support roller 40. In this manner a complete support of the cable is provided so that rotation of the drum in one direction will raise the gate and in the opposite direction will lower the gate.

The cable 15 passes around the guide rollers 50 and 51 beneath the support roller 52 for the counter-weight and then to the guide rollers 53, 54, 55, 56 and to the drum 31. After several 5 windings around the drum this cable then returns over the guide rollers 58, 59 and 60 where it passes downwardly to the support roller 61 for the counter-weight 71 and then upwardly to the other guide roller 62. The final guide roller 64 10 directs this cable back into the support 4 and upwardly to the final support roller 65 in the top of the support.

The counter-weights 70, 71 and 72 are supported by the various cables upon support rollers 46, 64 and 52, respectively, so that they will always cause a tension upon the cable. These 15 weights remain in a stationary position, however, upon raising and lowering of the gate because there is no change in the length of the 20 cable as it is reaved through the various support and guide rollers. When the gate is in closed position, however, if a vehicle or other object should run against the gate there would of course be a tendency for the gate to move laterally. 25 These counter-weights resist this tendency but the gate is permitted to move laterally if the impact is greater than the force required to lift these weights just described. If the impact is greater than of course the gate will move laterally, carrying the cables 15 and 16 with it and raising the weights somewhat. In this manner 30 there is always the tendency to slow down the object causing the impact and bring it to rest. Of course when the object is removed the weights 35 will return to their normal position and the gate will move to its position between the posts.

In view of the flexible nature of the gate and its support it is contended that little or no damage 40 will be caused to the vehicle because of its impact with it.

Fig. 6 shows a modified form of the invention where the parts are the same as described in connection with Fig. 1 except that the counter-weights 70 and 72 have been positioned above the 45 surface within the housing 80 and 81, respectively. In this modification the raising and the lowering portion of each of the cables 14 and 15 passes beneath one roller of the pair of rollers secured to the respective counterweights 10 and 12. The 50 guide and support rollers have been realigned in order to support the weights in a position to resist lateral movement. This construction is somewhat more economical to install because the additional excavations and footings are unnecessary. There is another advantage also in that 55 the space between the support post 4 and the housing 81 and the support post 5 of the housing 80 can be covered so as to rigidify the structure and also to provide additional display of sign spaces such as 82 and 83, respectively. The general arrangement and construction of Fig. 6 is the same as Fig. 1, and it is not believed necessary to describe it in detail.

In operation, if the gate is placed across a 60 highway at a railroad intersection an electric signal system may be installed and attached to the railway tracks so that the circuit will be closed to energize the motor 38 when a train approaches. The operation of the motor will then lower the 65 gate and retain it in lowered position so long as the train is within the signal block. When the train leaves the block, however, the circuits are opened and may be so arranged that the motor may be reversed and the gate raised to its position 70 as seen in Fig. 1.

This electric signal system forms no part of the present invention because such systems are well known.

In event the motor of the operating mechanism should be inoperative when the gate is in its 5 lowermost position it is desirable then to raise the gate so that it will not interfere with traffic. To accomplish this the counterbalance weights 90 and 91 have been suspended in the opposite sides of posts 5 and 4, respectively. These weights are 10 carried by separate cables 92 and 93, respectively, which pass over the support rollers 65 and 48 in the top of the framework and are then connected to the ends of the gate member in a suitable manner. Thus, if the gate should be inoperative 15 by its mechanism while in lower position it will only be necessary to release the clamps 17 and 22 from the cables 14 and 15 whereupon the counter-weights 90 and 91 would then raise the gate by sliding these clamps along the cables 14 and 15. 20

What is claimed is:

1. A gate of the character described comprising in combination a gate member, cable members connected to said gate at each end, support posts, means thereon to guide said cables, a drum about 25 which said cables are directed, motor means to rotate said drum to either wind or unwind said cables whereby said gate is raised or lowered, weight members supported by said cables and movable upon impact which tends to move said 30 gate laterally.

2. A gate of the character described comprising in combination a gate member, cable members connected to said gate at each end, support posts, means thereon to guide said cables, a drum about 35 which said cables are directed, motor means to rotate said drum to either wind or unwind said cables whereby said gate is raised or lowered, weight members supported by said cables and movable upon impact which tends to move said 40 gate laterally, and an additional set of weights and cables connected to said gate and arranged to raise the gate when it is released from said first cables.

3. A gate of the character described comprising 45 in combination a gate member, cable members connected to said gate at each end, support posts, means thereon to guide said cables, a drum about which said cables are directed, motor means to rotate said drum to either wind or unwind said 50 cables whereby said gate is raised or lowered, weight members supported by said cables and movable upon impact which tends to move said gate laterally, said weight members being disposed adjacent each of said support posts. 55

4. A gate of the character described comprising in combination a gate member, a closed cable member connected to said gate at each end, and connected to the gate from above and below, support posts, means thereon to guide said cables, a 60 drum about which said cables are directed, yielding means for applying a force to each flight of each of the cables to maintain the cables taut and to yield when a lateral impact is imparted to the gate member, motor means to rotate said drum to either wind or unwind said cables whereby said 65 gate is raised or lowered.

5. A gate of the character described comprising in combination a gate member, a closed cable member releasably connected to said gate at each 70 end, support posts, means thereon to guide said cables, means for moving said cables to raise and lower the gate, a weight supported upon both flights of each of said cables, and means for rais- 75

ing said gate when the gate is released from the cable members.

6. A gate of the character described comprising spaced vertical supports, a frame construction across the tops of said supports to provide display surfaces, to rigidify the structure, and to form a housing, a pair of spaced guide rollers on each of said supports, an endless cable member passing over each of said pairs of rollers, a flexible gate member between said supports, said gate having

each end connected to one of said cables, a drum about which each of said cables is passed for frictional engagement therewith, a motor means for driving said drum whereby the gate may be raised into or lowered from said housing, and a weight supported by each of said cables whereby the cable is maintained taut and the gate may move laterally upon impact therewith.
